CLAIM

The ornamental design for a foldable bowl, as shown and described.

DESCRIPTION

FIG. 1 is a perspective view of a foldable bowl showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a plan view thereof, shown unfolded.

The dash-dash-dash broken lines depict environment and form no part of the claim. The long dash-short dash line represents a boundary of the claim and forms no part of the claim.

1 Claim, 6 Drawing Sheets(56)
